EX

UNITED STATES PATENT OFFICE.

JOHN BROWN ALDEN, OF WORCESTER, MASSACHUSETTS.

DESIGN FOR CARPET.

Specification forming part of Design No. 6,970, dated November 4, 1873; application filed October 1, 1872.
[Term of Patent 7 years]

To all whom it may concern:

Be it known that I, JOHN BROWN ALDEN, of the city and county of Worcester, State of Massachusetts, have invented a Design for Carpets, of which the following is a specification:

The nature of my invention is fully shown in the accompanying photographic illustration, which shows a section of a carpet, which I make either by uniting a number of similar pieces together, or to alternate with other pieces of a plain ground or different patterns.

The design is composed of the following articles, viz: A sword, A, shield C, helmet D, spear E, two crossed battle-axes, G, gavel H, two shoulder-straps, i i, belt L, baldric N, and gauntlet O, with the capital letters F, C, B, K, and P, arranged substantially as shown, though they may be somewhat varied in position, as to form a square. I cross the spear and sword

at right angles, or nearly so, and separate their points still more, to make a section longer than high.

The ground-work and border may be of any desired pattern and color, and the articles named somewhat varied, though I prefer the following for them, to wit: The sword, spear, shield, helmet, and gavel, in silver, or the nearest to it; the belt and letter B in red; the letter F in blue; the letter C in yellow; the baldric and shoulder-straps in blue, silver, and yellow; and the gauntlet, letters K and P, and the battle-axes, in black, with a ground and lines to contrast well with these.

I claim—

The design above described and shown.
J. BROWN ALDEN.
